ELDER E. ANDERSON, OF MINNEAPOLIS, MINNESOTA.

ENVELOP-CUTTING MACHINE.

1,313,244.

Specification of Letters Patent.

Patented Aug. 19, 1919.

Application filed January 3, 1917. Serial No. 140,403.

To all whom it may concern:

Be it known that I, ELDER E. ANDERSON, a citizen of the United States, residing at Minneapolis, in the county of Hennepin and 5 State of Minnesota, have invented certain new and useful Improvements in Envelop-Cutting Machines, of which the following is a specification.

This invention relates to cutting implements, and particularly to devices for cutting paper.

The invention aims primarily to provide an improved envelop cutter, by the use of which envelopes may be cut evenly and 15 smoothly at one side or end so that the envelop may be preserved, and wherein the cutting action cannot impair the contents of the envelop. A still further object resides in the provision of a cutting implement which includes an improved guide, whereby cutting of the envelop inwardly from its edge beyond a predetermined distance will be prevented. Still further objects reside in providing a cutting mechanism of the character set forth which is 20 of extremely simple and inexpensive construction, which is formed of but few readily assembled parts, all of which are so assembled as to minimize the opportunity 25 for wear, breakage, or derangement, which is positive in operation, and which will prove thoroughly efficient in the attainment 30 of the ends set forth.

With these objects in view, together with 35 others which will appear as the description proceeds, the invention resides in the novel formation, combination, and arrangement of parts, all as will be described more fully hereinafter, illustrated in the drawings, and 40 particularly pointed out in the claims.

In the drawings:—

Figure 1 is a front elevation partly in section, of an envelop cutting machine constructed in accordance with the invention;

45 Fig. 2 is a sectional view taken upon line 2—2 of Fig. 1; and

Fig. 3 is a horizontal section taken on line 3—3 of Fig. 1.

Referring now more particularly to the 50 drawings, 4 indicates a base, preferably small and rectangular in shape, and which may be formed of wood. The block forming the base 4 is cut away on its upper surface to provide a groove or recess 5, the 55 said recess being arranged at one end of

the block and being disposed laterally thereof. A cutting blade 6, preferably of metal, rests within the groove of the recess 5, and may be secured to the block by screws 7. This metallic member constitutes a shearing edge for the knife to be hereinafter detailed, and is of a size equal to the space formed by the notch 5.

Secured to the forward end of the base 4 in any preferred manner is a yoke or 65 arch member 8, the legs of which are secured to the opposite sides of the base 4. The inner faces of these legs are provided with longitudinally disposed grooves 9, within which the opposing ends of a knife 70 blade 10 ride. The central portion or the top or bight member connecting the legs 8 of the yoke provides a vertically disposed barrel 11 through which slides a shank or plunger 12, the lower end of the said shank 75 being connected as by screws 13 to the blade 10. The upper end of the plunger 12 is provided with a head or knob 14, and an expansion spring 15 encircles the plunger, and bears at its ends against the head 14 80 and the barrel 11. This spring normally maintains the plunger in raised position, so that the cutting edge of the knife 10 is removed from the shearing blade 6 on the base.

85 It will be observed that the knife 10 is provided at its lower end with a cutting edge 16, the latter being beveled rearwardly as shown, and the said cutting edge is inclined slightly from one end to the other of the 90 blade. This inclination produces the desired shearing action as the blade is lowered. It will be observed particularly with reference to Fig. 2, that the forward edge of the blade 6 terminates in the same plane with the 95 rearmost walls of the grooves 9, and therefore, the blade in its downward movement will pass in close proximity to the forward edge of the blade. Stops 17 extend into the grooves 9 upon each of the yoke legs, and 100 these stops limit the downward movement of the shearing blade.

It will be realized that inasmuch as the stops are screwthreaded and movable into and out of the grooves, blade 10 is inserted 105 before they are projected into the grooves, or they may be withdrawn to permit insertion. After insertion of the blade, the stops are projected into the grooves so that the blade may rest thereon and be supported 110

thereby while the stem or plunger 12 is secured thereto through the medium of screw 13.

Arranged upon the forward edge of the base 4 is a gage 18. This gage includes an upwardly extending arm 19, which is disposed slightly beyond the path of travel of the blade 10, and the said arm limits the movement of envelopes projected beneath the arch from the rear of the base. By providing a gage of this character, all envelopes operated upon by the knife will have their edges cut an equal distance inwardly from the edge, whereby uniform cutting action of the instrument is maintained. It will be understood that envelopes to be cut are deposited one at a time upon the base 4, and moved forwardly upon the base and beneath the yoke 8. The arm of the gage will limit the movement of the envelopes, and downward movement applied to the plunger 12 will cause the edge of the envelop to be clearly cut. Immediately upon releasing the plunger, the latter moves upwardly under impulse of the spring 15.

While the present is a disclosure of what I believe to be the preferred embodiment of the invention, it is to be understood that the

invention is not limited thereto, but that various changes may be made in the construction, arrangement, and proportion of parts, without departing from the spirit of the invention, as defined in the appended claim.

What is claimed is:—

In a device of the class described, a one-piece frame having side bars, each side bar having a groove, a cutter slideable in said grooves, a base for the frame having means with which the cutter co-operates for shearing, detachable operating means for the cutter, and stop means movable into and out of the grooves to permit insertion of the cutter therein and to secure the cutter against accidental displacement from the grooves, and said stop means serving to support the cutter during attachment of the operating means thereto and to limit the downward movement of the cutter during operation.

In testimony whereof I affix my signature in presence of two witnesses.

ELDER E. ANDERSON.
